UNITED STATES PATENT OFFICE.

EDWARD W. KEATING, OF TERRE HAUTE, INDIANA.

TROLLEY-WHEEL FORK.

No. 829,109.

Specification of Letters Patent.

Patented Aug. 21, 1906.

Application filed February 3, 1906. Serial No. 299,308.

To all whom it may concern:

Be it known that I, EDWARD W. KEATING, a citizen of the United States, residing at Terre Haute, in the county of Vigo and State of Indiana, have invented a new and useful Improvement in a Trolley-Wheel Fork, of which the following is a specification.

My invention relates to that class of trolley-wheel forks which are used for the purpose of supporting and properly holding in place the trolley-wheel used for the purpose of holding and guiding the trolley-pole of an electric car or other similar vehicles in connection with the trolley-wire; and the objects 15 of my invention are, first, to provide a trolley-wheel fork whereby the trolley-wheel will be firmly held upon the trolley-pole and in safe connection with the trolley-wire; second, to provide such a fork which will prevent the trolley-wheel from being knocked from the trolley-wire by obstructions—such as cross-wires, switch connections, and other similar obstructions; third, to provide such a fork whereby in case the trolley-wheel meets 20 with an obstruction such as a cross-wire, which would naturally knock the wheel from the wire, the trolley-wheel will be protected and prevented from losing connection with the trolley-wire; fourth, to provide such a fork whereby all strain and jar occasioned by 25 the wheel meeting with obstructions will be received and compensated by the fork itself, thereby removing all danger of strain, bending, and breaking of the trolley-pole, so commonly experienced in the use of trolley-wheel forks used heretofore, and, fifth, to provide such a fork which will be substantial, efficient, durable, simple in construction, and economical.

40 I attain these objects by the mechanism illustrated in the accompanying drawings, in which—

Figure 1 is a side view of the trolley-wheel fork. Fig. 2 is a plan of the trolley-wheel fork. Fig. 3 is a sectional view of one of the hangers and the mechanism supported thereby.

The letter A indicates a fork consisting of a hollow shank a, which constitutes a socket for 45 the reception of the extreme end of the trolley-pole b, upon which the fork is mounted and held by a rivet c and two arms or prongs d. The two prongs d are provided at their extreme ends with hangers e and shaft-bearings p. The hangers e are integral with the

prongs of the fork and consist of two parallel walls i and i', which project upward from the upper edges of the two arms or prongs d of the fork A, thereby forming a channel or recess m between said walls for the purpose 60 hereinafter set forth. The walls i and i' are beveled downward right and left from the center of their upper edges, thereby forming a triangular outline, the apex of which is rounded and perforated horizontally for the purpose 65 of providing the shaft-bearings n. A threaded pin o or other substantial device is positioned at either end of the channels m for the purpose of holding the hereinafter-described springs s, as shown in Figs. 2 and 3. Immediately below the center of the hangers e the prongs d of the fork are perforated longitudinally for the purpose of providing shaft-bearings p, which support the shaft r of the trolley-wheel w. A grooved trolley-wheel w of 70 any of the well-known types is suspended between the prongs d of the fork A by means of a shaft r, upon which the wheel is keyed or otherwise fixed. A guide-rod t is suspended perpendicularly and movably between the 75 walls of the hangers e by means of shafts r', which find bearings in the shaft-bearings n in the walls i and i' and consist of a cylindrical shaft 2, a bearing-block 3, and a pendent hanger-like lever 4, all integral with each 80 other. The lower end of the cylindrical shaft 2 is slightly smaller than the upper face of the bearing-block 3 at the junction therewith and forms a shoulder 5, upon which a cylindrical sleeve 12 rests. The bearing-block 3 is perforated horizontally for the purpose of receiving the shaft r', upon which the guide-rod t is loosely mounted and the extreme 85 ends of which find bearings in the shaft-bearings n of the walls i and i'. The outer faces 90 of the two outer walls i are provided with notch-like recesses 7 for the purpose of permitting the passage of split pins 8, which confine the shafts r' within their bearings—with their outer ends flush with the outer 95 faces of the walls i in order that there will be no projection of shafts r' beyond the face of the walls i, and the inner ends of the shafts r' are provided with beveled heads which fit into the inner ends of the shaft-bearings n in the walls i', which are countersunk for the 100 reception of said beveled heads. Notch-like recesses 9 are likewise cut into the outer walls for the purpose of receiving the split pins 10, which confine the shaft r within its 105 110

bearings *p*. Two strong spiral springs *s* are attached at their inner ends to the extreme lower end of the pendent lever *4* of each of the guide-rods *t*, and their opposite ends are attached to the corresponding pins *o*, mounted in the extreme ends of the channel *m* of the hangers *e*. The springs *s* when normal counterbalance each other, and thereby hold the guide-rods *t* perpendicularly.

10 A loosely-fitting sleeve *12* is mounted upon each of the cylindrical shafts *2* and rest upon the shoulders *5*. The sleeves *12* are provided a short distance above the rims of the trolley-wheel *w* with downwardly-curving projections *u* for the purpose of preventing wires or other obstructions from catching between the sides of the wheel and the guide-rods and hangers. The shafts *2* of the guide-rods extend a short distance above the upper 15 ends of the sleeves *12* for the purpose of receiving pins *13*, which transfix the projecting ends of said shafts and are bent downward over the edges of the sleeves for the purpose of confining said sleeves upon the 20 shafts *2*.

When obstructions—such as cross-wires, switch connections, and similar obstacles—are met by the trolley-wheel the upwardly-projecting guide-rods *t* first strike such obstruction, and the force of the collision is transmitted to the springs *s*, which take up any strain occasioned thereby in their respective extension and compression, depress the trolley-wheel below the obstruction, but 30 still straddle the trolley-wire, and when free of the obstruction immediately resume normal position, thereby restoring the guide-rods to normal position and the trolley-wheel to the trolley-wire. The sleeves *12* 35 are loose upon the shafts *11* and are therefore free to revolve thereon while passing an obstruction, hence are subject to but little wear and no strain. The springs *s* receive and compensate the blow and consequent 40 strain occasioned by collision with an obstruction, and thereby relieve the trolley-wheel and trolley-pole of all danger of injury therefrom.

Having described my invention, its operation and purpose, what I claim as new and

useful, and desire to protect by Letters Patent, is—

1. In a trolley-wheel fork, the combination with a trolley-pole and trolley-wheel, of a two-pronged fork consisting of a shank, 55 two hangers supported by the prongs of said fork, and a shaft, adapted to support the trolley-wheel, two guide-rods suspended perpendicularly within said hangers, a double set of opposing springs in connection 60 with each of said guide-rods and said hangers, respectively, shafts adapted to support said guide-rods, a metallic sleeve mounted upon the upright shafts of said guide-rods, and pins, transfixing the upper ends of the 65 guide-rods and adapted to confine said sleeves upon said guide-rod shafts, all substantially as shown and for the purposes set forth.

2. In a trolley-wheel fork, the combination with a trolley pole and wheel, of a two-pronged fork, consisting of a socket-shank adapted to fit onto the end of the trolley-pole, two prongs, integral with said socket-shank and provided with shaft-bearings 70 adapted to support the shaft of the trolley-wheel, two hangers supported by the prongs of the fork, respectively, upon opposite sides of the trolley-wheel, a movable, upwardly-projecting guide-rod, suspended upon shafts, 75 within each of said hangers, a loose sleeve mounted upon each of the guide-rods, adapted to straddle and confine the trolley-wire, a downwardly-curving bar projecting from the walls of said sleeves, a double set of opposing springs, attached to the lower ends of each of the guide-rods and to the opposite ends of the hangers, respectively, adapted to control the guide-rods and to compensate all 80 shock and strain sustained by the trolley-wheel fork, all substantially as described and shown and for the purposes set forth.

In testimony that I claim the foregoing as my own I have affixed my signature in the presence of two witnesses.

EDWARD W. KEATING.
